[57] ABSTRACT

An adaptor system for use on a cigarette vending machine of the type in which the articles to be vended are in a tray-like magazine as a row of articles on edge with the leading article therein positioned to be engaged by a pick-up means which is carried by a vertically movable elevator, when a spring-actuating mechanism is coin-released to advance the magazine tray into vending position. The adaptor system includes stop means for predetermining the advanced position of the magazine tray in accordance with thickness of the article to be vended and attachment means which can be applied to the magazine tray to adapt it to articles of different thicknesses, widths and heights as well as attachment means which can be applied to the pick-up means to adapt it to articles of different sizes.

**ADAPTOR SYSTEM FOR A VENDING MACHINE
TO ADAPT IT TO THE VENDING OF VARIOUS
SIZE ARTICLES**

A type of cigarette vending machine now in use is known as "Tobacco Counter" and is manufactured by the Seeburg Corporation of Chicago, Ill. and is disclosed in publications of that company entitled "Parts Catalog No. 135,399, Installation and Operation Manual No. 135,315, and Service Manual No. 135,398."

This cigarette vending machine has tray-like package-receiving magazines mounted in laterally spaced relationship for horizontal reciprocation under the control of trigger-released spring arrangements. Each magazine tray is adapted to receive a row of cigarette packs with the packs disposed upright on an end edge in back-to-face contact and a spring-actuated pack pusher is provided in each magazine for pushing the row toward an outer vending position in an end of the magazine. At this end of the magazine, there is a product guide and stop arrangement which includes vertically extending, laterally spaced stop flanges with a slot formed therebetween through which a vertically moving pick-up finger or tang can pass after it engages the lower edge of the leading pack in the magazine so as to lift it therefrom. The pick-up fingers are on pack-receiving buckets which are mounted in laterally spaced series of vertically spaced buckets on endless carriers forming part of a pack-delivery elevator system, the series of buckets are aligned with the respective magazine trays and are normally spaced outwardly therefrom and stationary. When the proper coins are inserted in the machine, the trigger-actuated spring mechanism is released to permit the selected magazine to be advanced into vending position and, simultaneously, the elevator is driven upwardly to move the proper pick-up finger into engagement with the leading pack in that magazine so as to strip it from the magazine into the adjacent upward-traveling elevator bucket. The bucket after reaching the peak of its travel, tilts outwardly and ejects the package onto a delivery counter.

This type of cigarette vending machine is limited to the vending of packs of a certain thickness, due to the fact that each magazine must be advanced to a vending position, which is determined by the thickness of the packs being vended, in order for the elevator pick-up fingers to properly engage the leading pack in the magazine. Also, the magazine tray itself, and the product guide and stop flange arrangement at the vending end thereof, are designed for a certain thickness, width and height of pack.

It would be desirable to adapt this type of cigarette vending machine and other similar machines to the vending of other articles which may be of different dimensions, either in thickness, width or height, or all three. The present invention provides a simple adaptor system having parts which can be attached readily to this type of machine so that it can vend articles or packages of the different sizes.

This adaptor system includes, generally, stop means for changing the advanced vending position of the magazine trays relative to the pick-up fingers carried by the elevator so that packages of different thicknesses will be engaged, and adaptor means to be applied to the magazine trays so that they can handle packs of different thicknesses, widths and heights than those for

which they were designed and including package or product guides at the vending ends thereof. These various elements can be used individually or in combination. In addition, the pick-up means associated with each elevator package delivery bucket can be provided with an adaptor which makes it adjustable so as to properly engage and eject packs of different heights in the magazine trays.

The best mode contemplated in carrying out this invention is illustrated in the accompanying drawings in which:

FIG. 1 is a top perspective view of a magazine drawer assembly of a type of cigarette vending machine to which this invention is applicable.

FIG. 2 is a perspective view of one of the removed magazines.

FIG. 3 is a bottom perspective view of the drawer assembly shown in FIG. 1.

FIG. 4 is a perspective view showing a rear portion of the drawer assembly and a portion of a cooperating package delivery elevator.

FIG. 5 is a view partly in side elevation and partly in vertical section of the elevator and its cooperating package ejector.

FIG. 6 is a bottom plan view of magazine latching mechanisms of the drawer assembly showing them equipped respectively with different forms of a magazine stop arrangement according to this invention which adapts the machine to the vending of thinner articles.

FIG. 7 is a vertical sectional view taken along line 7-7 of FIG. 6.

FIG. 8 is a perspective view of a stop plate of a type used in FIG. 6.

FIG. 9 is a similar view of another form of stop plate of a type used in FIG. 6.

FIG. 10 is a perspective view of a stop plate of a type used as in FIG. 11 to position a magazine.

FIG. 11 is a bottom plan view showing a magazine provided with the stop plate of the type shown in FIG. 10.

FIG. 12 is a vertical sectional view showing the inner or vending end of a magazine and another form of stop plate cooperating therewith.

FIG. 12a is a perspective view of the stop plate used in FIG. 12.

FIG. 13 is a vertical sectional view taken longitudinally through one of the magazines and showing it equipped at its vending end with product guides for packages of varying thicknesses, widths and heights.

FIG. 14 is a transverse vertical sectional view taken on line 14-14 of FIG. 13.

FIG. 15 is a plan view of the structure of FIG. 13.

FIG. 16 is an elevational view taken from the position indicated at line 16-16 of FIG. 13 at the outer or vending end of the magazine.

FIG. 17 is a transverse vertical sectional view taken along line 17-17 of FIG. 13.

FIG. 18 is a view partly in side elevation and partly in vertical section showing how an elevator bucket in its vertical movement cooperates with a magazine equipped with an adaptor arrangement of the type shown in FIGS. 13 to 17.

FIG. 19 is a similar view but indicating the elevator bucket raised to successively higher positions.

FIG. 20 is a similar view but showing the elevator bucket at a still higher position and equipped with a

pick-up finger which is adjustable for packages of various heights.

FIG. 21 is a horizontal sectional view taken along line 21—21 of FIG. 20.

FIG. 22 is a perspective view of the pick-up finger.

FIG. 23 is a perspective view, partly broken away, of the adaptor used in FIGS. 13 to 21 and showing it removed from the magazine.

FIG. 24 is a view showing an adaptor similar to that of FIG. 23 but having front plates of substantial thickness to adapt a magazine to the vending of thinner articles without the use of any of the magazine stops previously mentioned.

FIG. 25 is a view in side elevation, partly broken away, showing the adaptor of FIG. 24 positioned in a magazine and showing an elevator bucket cooperating therewith.

FIG. 26 is a horizontal sectional view taken along line 26—26 of FIG. 25.

FIG. 27 is a transverse vertical sectional view taken along line 27—27 of FIG. 25.

FIG. 28 is a plan view of an adaptor in use with a magazine at the vending or outer end thereof as a package or product stop adjustable for packages of varying thicknesses and heights.

FIG. 29 is a perspective view of the structure of FIG. 28.

FIG. 30 is an enlarged horizontal sectional view taken along line 30—30 of FIG. 29.

FIG. 31 is a view of an adaptor similar to that of FIG. 28 but also equipped with means for adapting to packages of varying widths as well as varying thicknesses and heights.

FIG. 32 is a perspective view, partly broken away, of the adaptor of FIG. 31.

FIG. 33 is an enlarged horizontal sectional view taken along line 33—33 of FIG. 32.

FIG. 34 is a plan view of another type of magazine adaptor provided with adjustable wall and product stop means to adjust for articles of varying widths, heights and thicknesses. FIG. 35 is a vertical sectional view taken along line 35—35 of FIG. 34 longitudinally through the magazine.

FIG. 36 is an enlarged horizontal sectional view taken along line 36—36 of FIG. 35.

FIG. 36a is a sectional view showing the use of fastening tape on a lamination of the type shown in FIGS. 35 to 38.

FIG. 37 is a vertical transverse sectional view taken along line 37—37 of FIG. 35.

FIG. 38 is a perspective view of the adapter of FIGS. 34 to 37 with parts separated.

With specific reference to the drawings, FIGS. 1, 2 and 3 illustrate a drawer 40 used in a cigarette vending machine of the type previously disclosed. This drawer carries a series of cigarette-pack magazines 50 which are of tray-like form and are disposed in laterally spaced relationship for longitudinal reciprocation for cooperation with a delivery elevator 60 which receives the packs as they are lifted from a coin-selected magazine tray and carried thereon upwardly to a delivery point where they are discharged on a counter top indicated generally at 70 in FIG. 5.

Several of the drawers 40 are usually provided in the cabinet of a machine of the type indicated at various levels. They are usually mounted in the cabinet of the machine for in-and-out sliding movement on roller

guides (not shown) which cooperate with the guideways or slide channels 41 disposed at opposite sides of the drawer and extending longitudinally thereof. Each drawer has a front panel 42 on which are mounted the cigarette pack selecting buttons 43 which are substantially aligned with the respective magazines 50 and can be used to select a particular magazine containing packs P of cigarettes desired, when a proper coin is inserted. The coin-operated selecting mechanism is not illustrated as it is not important to the present invention. It will be noted (FIG. 3) that mounted beneath the drawer at its inner end, is a plate 44 which carries resilient tongues 45 at its extremity. This plate has notches 45a which permit vertical movement of certain parts of elevator 60. Above the plate 45 is fastened magazine stop bar 44a.

The structure of each of the magazines 50 is illustrated best in FIGS. 2, 4, 12 and 13. The magazine as indicated, is of drawer or tray-like form, being elongated and narrow, having a flat bottom 51 with upstanding opposed side walls 52 extending the full length thereof. The one end, which may be termed the loading end 53 can be open, and the other end, which can be termed the vending end 54, is provided with stop and guide flanges 55, with which the leading pack in the magazine is adapted to engage. The flanges 55 are in a pair of opposed flanges which extend inwardly towards each other at right angles to the side walls 52. They are spaced apart to provide a vertical slot 56 therebetween which communicates with an aligning slot 57 at its lower end that extends into the flat bottom 51. The upper edge of each wall 52 may be provided with a reinforcing lip 58 and each wall may be provided with an upwardly opening notch 59 adjacent its flange 55. One side wall 52 is provided with an outwardly extending pin 61 substantially midway of its length. This wall also carries a magazine return lever 62, pivoted thereto for vertical swinging movement by a pin 63 and adapted to be engaged in its upward swinging movement by a pin 64 carried by the side wall 52. The bottom 51 is provided with a pair of laterally spaced grooved guide rollers or collars 65 at one end and with a second pair of identical rollers or collars 66 at the other end. Substantially midway between the two pairs of collars 65 and 66, the bottom is provided with a depending guide and lock pin 67 located along its longitudinal center line.

Each of the magazines has formed on the upper surface of the bottom 51, a pair of opposed pusher guides 68 (FIGS. 13 and 14) extending the full length thereof for cooperating with the upstanding pack pusher 71. This pack pusher is biased on the guides 68 toward the vending end 54 of the magazine by means of a retractable winding spring unit 72 (FIG. 13) which is carried by the pusher and which has the free end of its spring anchored to the bottom plate 73 of the drawer 40 by means of a screw 74. It will be noted that the spring unit 72 is carried by a transverse shaft 72a which is slipped into outwardly opening slots 76 formed in upright walls 77 which brace the pusher face plate that contacts flat with the last pack in the magazine 50. The slots 76 face in the opposite direction to the direction of pull by the spring of unit 72 and, therefore, the shaft 72a will be retained therein normally. However, the shaft can be pulled out of the slots, when desired, to disconnect the pusher 71 from the spring unit. Normally the spring unit advances the pusher on the magazine 50 to push the packs P forwardly to vending position in the ma-

zine as the levelling pack is successively removed. The magazine spring unit 72 serves another function of moving the selected magazine 50 forwardly into vending position in cooperation with the elevator 60, as will be described later.

The magazines 50 are slidably carried on the drawer plate 73, for individual reciprocation, in laterally spaced relationship. For mounting each magazine, the pairs of flanged guide collars or rollers 65 and 66 are disposed for longitudinal movement in respective pairs of guide slots formed in the plate 73, the flanges being above and below the plate, respectively. Slots 75 are shown in FIGS. 6 and 11 for receiving the collars 65 and slots 78 are shown in FIGS. 3, 12, 20 and 25 for receiving the collars 66. Also, the plate 73 is provided with a longitudinal slot 79, as shown in FIGS. 3, 6 and 11, through which the stop pin 67 of the magazine depends and reciprocates.

In this type of vending machine, the selection of a particular magazine 50 for dispensing packs P therefrom, is by the respective buttons 43. The magazines are locked in their non-vending position by magazine latching units 80, which are shown best in FIGS. 3 and 6, and which cooperate with the depending lock pins 67 on the bottoms of the respective magazines. These units are mounted at the lower side of the plate 73.

Each latching unit is substantially of the type disclosed in U.S. Pat. No. 3,493,144 to Johnson, issued Feb. 3, 1970. Each of these units functions substantially in the manner described in said patent and is actuated by means of a slide 30. The slides 30 are mounted for reciprocation below the plate 73 by means including a transversely extending inner support plate 81 (FIG. 3) and outer laterally spaced support plates 82 which are aligned with the respective magazines, the plates 81 and 82 being spaced below the plate 73. Each plate 30 (FIG. 7) slidably extends through an upstanding flange 83 in the plate 81 and adjacent its outer end is provided with an upstanding lug 84 which is spaced inwardly from an upstanding flange 85 at its outer extremity. Between the lug 84 and flange 85 is a compression spring 86 which has its inner end fitting in a cup 87, fixed to the lug 85, and its outer end fitting into a cup 88 carried on the inner end of the rod 89 slidably mounted in a depending flange 90 on the outer end of the plate 73. The associated hinged button 43 engages the outer end of the rod 89 and when pushed will move the rod inwardly, partially compressing the spring 86 and sliding the plate 30 inwardly. A tension spring 69, secured to slide plate 30 (FIG. 6) and anchored to the flange 90, tends to return the plate 30 to its normal or outer position after being stretched by inward movement of the plate.

Inward movement of a plate 30 by its cooperating selection button 43 results in actuation of the respective latching unit 80 to release the stud or pin 67 of the selected magazine 50, which carries it, so as to permit spring 72 to move it to vending position as determined by its collars 66 engaging stop bar 44a (FIGS. 3 and 12). The latching units function as described in said patent so that when button 43 is pushed and actuator slide plate 30 is advanced, the magazine latch 14 is pivoted to release the stud 67 allowing the magazine to slide rearwardly into vending position. A safety latch 32 locks the slide 30 in its rear position holding the selection button 43 inwardly. The auxiliary latch 6 is positioned to catch the magazine stud 67 in retatching if the

button 43 is held in. After vending, the stud 67 is returned to latched position in a manner to be described later.

The actuator slide plate 30, in its rearward or inward movement, also actuates a series of laterally slidable lock bars 91. These lock bars are slidably mounted between the plate 81 and the plate 73. These bars are moved laterally by means of a pair of rollers 92, carried on the lower side of each slide 30, and which engages corner surfaces 93 on adjacent pairs of the bars 91 to spread them apart. This lateral movement of these bars controls the sequence of operation of certain units of the machine, including the elevator unit 60, but the details of this control mechanism are not important to the present invention.

When the selected magazine is moved as indicated to its vending position, the elevator 60 (FIGS. 4 and 5) is simultaneously actuated to cause the buckets 95 thereof to move upwardly, one series of these buckets being aligned with the selected magazine. The buckets 95 are supported in series of vertically spaced buckets on transverse supports 96 which are carried by endless chains 97, one of which is shown in FIGS. 4 and 5. Each bucket is open at its top but carries at its lower end a pick-up finger or tang 100. The bucket will move upwardly past the end of the selected extended magazine 50, the pick-up finger 100 passing upwardly through the slot 57 at the end of the magazine to engage the bottom end of the leading pack P in the magazine and strip it from the exposed end of the magazine so that it will be disposed in the rearwardly tilted bucket as shown in FIG. 4. As the elevator reaches the top of its travel, a projection 101 on the bucket assembly hits a stop bracket 102, carried by a vertical support 103, and causes the bucket to swing about its pivotal mounting 104. The inner run of the chain moves upwardly and its outer run moves downwardly so that the pin 106, carried by the latch 105, engages with cam edge 107 on a bracket 108 carried by the upstanding elevator support 109.

This removes the latch notch 110 from the pin 104 and swings the bucket 95 forwardly or outwardly, causing the pack P to tilt downwardly out of the bucket onto an inclined chute 111 so it will slide down onto the counter top 70. Reverse movement of the elevator 60 will occur at the proper instant and this will tilt the bucket back or outwardly to its original position and again latch it in that position.

As shown in FIG. 4, the inner run of the chain carries a cam bracket 114 at a selected position and this bracket has fixed thereto a cam 115. As the pack-receiving bucket 95 is raised by the elevator, this cam engages and swings upwardly a magazine reset cam rocker arm 116 which is pivoted to the side of the drawer 40 and is normally biased downwardly by a spring 117. This arm 116 rocks a transverse shaft 118 which carries a series of magazine reset cranks 119 provided for cooperation with the respective magazine return levers 62 previously mentioned. Thus, the lever 62 of the selected magazine 50 will be swung upwardly to engage the stud or pin 64 of that magazine and will slide the magazine forwardly to its original position, where the stud 67 of that magazine is again positioned in its cooperating latching unit 80 to hold the magazine in non-vending position until it is again selected.

The various units of the machine so far described are present in a vending machine of the type to which the

present invention is applicable. The adaptor system of this invention, which makes it possible for that machine to handle articles of different thicknesses, widths and heights, than the articles for which it was designed to vend, will now be described.

It will be apparent from the above that in the operation of this machine without the adaptor system of this invention, the vending position of a selected magazine is accurately determined by the collars 66 of that magazine striking the stop bar 44a and specifically the curved stop rib 44b (FIG. 12) which is at the inner edge thereof, the bar being bolted to the lower surface of the plate 73. This will determine the extended or vending position of that particular magazine relative to the elevator 60. This position will be predetermined in accordance with the thickness of the package to be stripped from the extended magazine, since the stop flanges 55 locate the leading pack P at a predetermined position in the vending end of the magazine and the collars 66 engaging stop rib 44b, locate the magazine in an advanced position relative to the pick-up finger 100 which is to lift the leading pack from the magazine. The adaptor system of the present invention provides additional, preferably variable, stop means for determining the advanced position of a magazine 50 so that packs of a different thickness than that for which the machine was designed, can be vended. This additional stop arrangement is illustrated in FIGS. 6, and 8 to 12.

In the form of the stop arrangement shown in FIGS. 6 and 9 it comprises a flat stop lug which is associated with the respective slot 79. Thus, in FIG. 8 there is shown a stop lug 125 which has a pin-engaging stop tang extension 126. The body of the lug is provided with longitudinal slots 127 for mounting the lug on the lower surface of the drawer plate 73 which supports the associated latching units 80. The stop lug is mounted on the lower surface of the plate 73 by means of clamping screws 128 which are passed through the slots 127 and threaded into the plate 73. In this form of stop, the flat tang extension 126 will extend over the slot 79 and between the auxiliary latch 6 and the plate 73 as shown in FIG. 6. The tang 126 will have its end extremity positioned along the slot 79 to stop the movement of the pin 67 and the magazine 50 which carries it at a precise vending position determined by the thickness of the articles in that magazine to be vended. Variable thicknesses may be accommodated by adjustment of the lug 125 relative to the slot 79 which will be permitted by loosening and re-tightening of the screws 128.

The stop arrangement shown in FIG. 9 is slightly different from that shown in FIG. 8. In this instance, the tang extension 126a is in a different plane from the body 125a. As shown in FIG. 6, this makes it possible for the extension 126a to extend beneath the auxiliary latch 6, it being remembered that FIG. 6 is a bottom plan view. This stop extension 126a works exactly as before in contacting the stud 67 but will be located in a different horizontal plane as compared to the extension 126. This stop 126a is used if the latch 6 is located too close to the plate 73 to permit insertion between these members.

Instead of the stops cooperating with the studs 67 to determine the final vending position of the respective magazines 50, the stops may cooperate with either guide collars 65 or guide collars 66 for the same purpose. Thus, in FIG. 10 there is shown a stop lug 130 which has a pair of laterally projecting tang extensions

131. Also, this member is provided with mounting slots 132 which can be used, as shown in FIG. 11, for receiving clamping screws 133 to adjustably clamp the member 130 to the plate 73. A pair of these lugs 130 will be used with the respective collars at opposite sides of the magazine 50 which is to be stopped thereby. The collar 65 at each side (FIG. 11) is shown disposed between the tangs 131 for reciprocation with the magazine. The inner tang 131 at each side, will contact with the cooperating collar 65 to determine the advanced or extended position of that magazine.

The stop arrangement shown in FIG. 12 and 12a is somewhat different but accomplishes the same purpose as the stop arrangement of FIG. 11. This stop comprises a plate 135 having slots 136 for receiving clamping screws 137, shown in FIG. 12, to clamp the plate adjustably to the plate 73, as shown in FIG. 12. At a lower level the plate is provided with a pair of extensions 138, each having an upstanding stop shoulder 140 at its outer extremity. The plate 135 is so mounted that its extension 138 will be below the guide collars 66 of the magazine 50. To limit the extended vending position of the magazine, the collars 66 thereof will contact with the upstanding shoulders 140 carried at the outer extent of the extension 138 rather than with stop rib 44b. The longitudinal position of shoulders 140 may be varied by the screw and slot adjustment including the screws 137.

Thus, it will be apparent that various adjustable stop structures are provided for accurately determining the final extended or vending position of a selected magazine 50. This final position will be selected in accordance with the thickness of the packs P which are contained within that magazine and are adapted to be stripped therefrom by the pick-up finger 100 of the elevator 60. If necessary, because of the change in the stopped final vending position of the magazine, the pin 64 on that magazine may be provided with a sleeve 64a (FIG. 4) to advance the time of engagement of the lever 62 and the stud assembly. Also, the pin 61 may be provided with an elevator start bar cam 61a to change the timing of the elevator start switch (not shown).

In FIGS. 13 to 21 and 23 a magazine 50 is shown equipped with an adaptor system for adapting it to the vending of packages P of various thicknesses, widths, and heights. This system can be used with any of the magazine stops previously described.

This adaptor system includes a pair of front mounting plates 145 which are adapted to be disposed upright in face contact with the inner surfaces of the respective flanges 55 at the vending end of the magazine 50. These plates are mounted in fixed outwardly spaced relationship, to permit movement of the pick-up finger 100 upwardly therebetween, by means of clamping screws 146 (FIGS. 13 and 16) passing through the magazine flanges 55 into the plates.

The plates 145 also carry the vertically disposed lower product guides 148 which are of angular cross-section. These guides are provided as a pair, and are mounted so that one flange 149 is parallel to its associated plate 145 and the other flange 150 is parallel to the associated side wall 52 of the magazine 50. The guides 148 are supported in laterally spaced upright position by means of the threaded studs 151 which are rigidly carried by the flanges 149 and project outwardly through the transverse slots 152 on the plates 145 adja-

cent their upper end and which carry clamping nuts 153 at the outer faces of the plates 145. Thus, the product guides 148 may be adjusted laterally to vary the spacing of the flanges 150 thereof. The product guides 148 provide a vertical guide channel behind the plates 145 which is of selected width. To compensate for difference in thicknesses of the products P in the magazine 50, the members 148 may be adjusted towards and from the plates 145 by means of the studs 151 and cooperating nuts 153.

A pair of upstanding upper product guides 155 are located above the guides 148 to provide a vertical continuation of the product guide channel provided by the guides 148. These members 155 are angular members similar to the members 148 and are similarly disposed in upright position, being adjustably mounted on a transverse horizontal support bar 156. The bar 156 is carried by studs 157 which are rigidly carried by the plates 145 and project inwardly therefrom through the bar, being provided with clamping nuts 158 on opposite sides of the bar. Thus, the guides 155 may be adjusted toward and from the plates 145 in accordance with the thickness of the packs P being dispensed by sliding bar 156 on the studs 157 and clamping it in place by the nuts 158. The guides 155 are mounted for lateral adjustment on the bar 156 to space them to correspond to the spacing of the product guides 148. For this purpose each of the guides 155 is provided with a square loop 160 (FIGS. 15 and 16) which slides over the square bar 156. A set screw 159 may be tapped through each loop 160 to engage the bar 156 and hold the guide 155 in laterally adjusted position. The block 173 is provided with an upstanding plate 179 which extends upwardly between the members 155 and is adjustable vertically with the block. The guides 155 are used when the packs P being vended are relatively short so as to guide the packs over the upper ends of the plates 145 and prevent them from falling back.

In order to properly center the packs P in the magazine 50 if they are of less width than the spacing of the walls 52 of the magazine 50, a pair of product guide rods 161 are provided within the associated side walls for engagement with the sides of the packs P. These rods have nuts 162 disposed within sockets 164 in the outer surfaces of the respective mounting plates 145 and have threaded portions extending through the plates. Rods 161 (FIG. 21) extend along the flanges 149 of the product guides 148 and are secured thereto by clamps 163. The sockets 164 surround transverse slots 165 in the plates 145 which permit lateral adjustment of the rods 161 towards and from each other in accordance with the width of packs being vended. The rear ends of the rods 161 pass through similar slots 166 in an upstanding transverse plate 167 which is part of a rod stabilizer bracket 168, the rods being threaded where they pass through the plate and carrying the clamping nuts 169 at opposite faces of the plate. The bracket 168 is of tray form, fitting within the side walls of the magazine and being suspended thereon by means of hooked upper edges 170 on its side walls which are disposed within the side walls 52 of the magazine, the hooks fitting over the upper edges of these side walls (FIG. 14) adjacent the leading end of the magazine.

An additional product hold-down rod 171 is provided and extends most of the length of the magazine 50 for engaging the top edges of the packs P thereon. This rod has a laterally turned end 172 at the vending end of the

magazine which is pivotally carried by a transverse pivot block 173. This block 173 is supported rigidly on the lower end of a rod 174 which has a threaded upper end extending slidably through the transverse support bar 156 and carrying clamping nuts 175 above and below the bar. Thus, the vertical position of the suspended block 173 and the rod 171 and plate 179 carried thereby can be adjusted. The rod 171 extends longitudinally through the upper portion of the magazine 10 and through the plate 167 of the bracket 168, passing through an upwardly-opening vertical slot 176 therein. At opposite sides of the plate 167, the threaded portion of the rod carries the clamping nuts 177 for engaging the plate. The block 173 carries an upstanding plate 179 which provides a vertically adjustable product stop 15 extending upwardly between the product guides 155.

It will be apparent that this adaptor system is made as an assembly which can be readily mounted in a magazine 50 or be removed therefrom. The only change required in the magazine is the boring of the holes in the flanges 55 to receive the screws 146. The packs P will be advanced in the magazine, being pushed along on the upstanding guides 68 until the leading pack P contacts the flanges 149 of the product guides 148 at 20 the vending end of the magazine 50. During this advance movement, the rods 161 engage the sides of the pack and the rod 171 engages the top edges. The product guides 148 and 155 guide the vertical movement of the pack lifted from the vending end of the magazine 25 by the lift finger 100. Adjustments of these product guides may be made in accordance with the width, height and thickness of the packs being vended.

It will be apparent that the adaptor assembly illustrated in FIGS. 13 to 21 and 23 may be used with any 30 of the magazine stop assemblies previously described. Also, it will be apparent that the various stop systems 35 may be used without the adaptor assembly.

The advanced pack P which will be in contact with the product guides 148 will be stripped from the vending end of the advanced magazine 50 by the pick-up finger 100 of the vertically moving elevator 60 in the manner indicated successively in FIGS. 18 and 19. The finger 100 of the vertically moving elevator 60, will engage the lower end of the leading pack P and lift it 40 through the vertical channel provided by the guides 148. As it leaves the upper end of that channel it moves into the channel provided by the upper guides 155 and will start to tilt outwardly over the upper ends of the plates 145 and eventually will tilt into its final position 45 within the bucket 95 which carries that particular finger 100.

For vending relatively short or thin packs P, it may 50 be desirable to have a vertically adjustable ejector finger or pick-up finger. Therefore, the arrangement shown in FIGS. 20 to 22 may be desirable to provide the adjustable finger 100a which will be disposed above the usual finger 100. This finger will be on the lower end of a plate 180 which is disposed upright with its outer face in flat contact with the inner face of the vertical outer wall of the bracket 95. The plate 180 is provided with a pair of vertical slots 181 through which clamp screws 182 are passed and tapped into the wall 95 of the bracket and the support 96 behind the bracket. This provides an arrangement whereby the finger 100a can be adjusted to different levels in the bracket and fixed in the selected vertical position. The finger 100a may be of various selected widths depend- 55

ing on the width of the article being vended and the width of slot 56.

The adaptor assembly shown in FIGS. 24 to 26 is to compensate for variations in thickness of the packs P without the use of the various magazine stops previously described. It is made as a separate assembly as shown in FIG. 24 for mounting in a single manner in the magazine 50. It may be mounted by the use of simple screws 146, as before, on the outer flanges 55 of the magazine. This assembly will not only compensate for differences in thickness of the packs P but parts thereof may be adjusted in accordance with variations of width and height of the packs being vended.

In this assembly plates 145a are provided which are similar to the plates 145 previously mentioned but are of substantial thickness. The thickness of these plates is selected to correspond to the difference in thickness of the pack P, usually vended in that magazine, and that of the thinner article to be vended after the magazine is equipped with this adaptor assembly. Each plate is notched at its inner and upper corner as indicated at 183. Adjacent its lower end, each of the plates 145 is notched at 164a where a transverse slot 165a is provided for receiving the end of the product guide rod 161a. Thus, the spacing between the rods may be adjusted in accordance with the width of the pack P to be vended in the selected magazine. The remainder of the assembly is similar to the one previously described, with rods 157a extending rearwardly from the plates 145a, adjacent their upper ends, and carrying the bar 156a which, in turn, carries the laterally adjustable product guides 155a. The bar 156a also carries the vertically adjustable product stop 179a which is supported by block 173a carried by the suspending stud 174a as before. The block 173a supports the product hold-down rod 171a and this is vertically adjustable with the block 173a in accordance with the height of the product being bended, the product stop 179a being simultaneously vertically adjusted.

This attachment will function to change the ejection plane of the leading pack P in the magazine which will be stopped at the inner faces of the plates 145a instead of at the inner surfaces of the laterally spaced flanges 55 of the magazine where the leading pack is usually stopped. Thus, a different ejecting plane is provided by the plates 145a which are of a predetermined thickness corresponding to the difference in thickness between the thinner product to be vended and the original cigarette pack for which the magazine and associated ejecting mechanism were designed.

With this particular attachment a rod stabilizer corresponding to the stabilizer 167, previously described, will again be provided at the loading end of the magazine.

This arrangement provides inwardly set stops for stopping the leading article at a different ejector plane, the stops being laterally spaced to provide an ejector slot through which the pick-up finger 100 can pass and strip the pack from the new ejector plane. It will be apparent that the slot between the stop plates 145a will align with the slot 56 provided between the opposed inner edges on the original stop flanges 55 of the magazine 50. As indicated, compensations for differences in thickness, width and height of the package to be vended, may be made with this assembly.

FIGS. 28 to 30 show a different type of adaptor assembly which can easily be mounted at the vending end

of a selected magazine 50. This assembly comprises the mounting and thickness compensating plates 145b which are disposed within the stop flanges 55 and provide stop surfaces inwardly of the flanges for engaging the leading article. These plates are held in place by clamping screws 146b which are tapped thereinto by first passing through the flanges 55. These screws also hold in place the angular mounting brackets 185 for vertical adjustment on the flanges 55, the screws passing through vertical slots 186 in the front flanges 187 thereof which overlap the flanges 55. The main flanges of the brackets 185 overlap the sides 52 of the magazine and extend upwardly beyond the upper edges thereof, the plates 145b being of similar vertical extent. 5 A product stop 190 is provided in straddling relationship to the upper ends of the brackets 185 and is of yoke form having downwardly extending tabs 191 and an upwardly extending stop and guide flange 192 for engaging the upwardly moved pack P as it is stripped 10 from the magazine. The flange 192 may be adjusted in or out, depending on the thickness of the pack being vended by means of screws 193 passing through longitudinal slots 194 in the tabs 191 and tapped into the members 185. 15 The parts of this assembly may be mounted on the usual magazine stop flanges 55 merely by providing tapped openings in the flanges for receiving the screws 146b. The assembly may be varied to compensate for height and thickness variations in the products being vended. The plates 145b may be of substantial thickness to take care of substantial variations in thickness. The assembly may be used with or without any of the various stop arrangements previously described for limiting the final extended position of the magazine. 20 25 The adaptor assembly shown in FIGS. 31 and 32 is similar to that shown in FIGS. 28 to 30 but includes a pair of upper product guides 155c and a product stop plate 179c. The parts 145b and 185, and 190 are substantially the same as before and mounted on the magazine flanges 55 in the same manner. The upstanding product stop and guide flange 192c is substantially the same as before but is provided with transverse slots 195 used in mounting the guide angles 155c for lateral adjustment in accordance with the width of the product. 30 35 These slots receive the mounting screws 196 and to prevent tilting of members 155c, each is provided with a lip 155d engaging the top edge of flange 192c. The flange 192c is also provided with a vertical slot 197 for receiving a screw 198 used in mounting the plate 179c for vertical adjustment. 40 45 50 This assembly will function the same as the one previously described except that it will have the upper vertically disposed product guides 155c and the vertical product stop plate 179c disposed therebetween. The guides 155c may be varied in lateral spacing in accordance with the width of the product and the plate 179c may be adjusted vertically in accordance with the height of the product. If desired, a hold-down rod 171c may be provided and when so provided will be pivotally attached to the lower end of the plate 179c as indicated at 199. 55 60 65 The adaptor assembly shown in FIGS. 34 to 38 may be used in a selected magazine with or without the various described stop arrangements for stopping the magazine at its extended vending position. This assembly will provide for variations in thickness, width and height of products or packages to be vended. The as-

sembly is such that it can be mounted in the magazine without any changes to the magazine.

Within each side wall 52 of the magazine a laminated unit 200 may be provided which can consist of any number of laminations. The laminations may be relatively adjustable in face contact in any direction that is vertical or longitudinal. The laminations are preferably formed of sheet steel and may be secured to each other by the material thereof being magnetized, by means of magnetic tape carried by one of the contacting faces, or by double adhesive tape disposed between the faces. For example, in FIG. 36a there is illustrated a strip of magnetic tape 200a on one of the members but, in the other FIGS. 34 to 38, no fastening tape is shown and it will be assumed that in these Figures, the laminations will be secured to each other in adjusted position by inherent magnetic attraction. The laminated side wall unit 200 at each side is shown as consisting of four laminations or side wall strips 201, 202, 203 and 204. At least one of the laminations, for example 202, is provided with the stop flange 205 which will be disposed within and substantially coextensive with the magazine stop flange 55 to serve as an additional stop flange inwardly of and adjustable relative to the flange 55 both laterally and vertically, as well as inwardly to change the plane of ejection and compensate for a difference in thickness of the product. Of course, in those adjustments the entire lamination 202 will be adjusted to position the flanges 205 as desired.

The laminations 201 and 203 may be mere spacer strips to provide for products in the magazine of varying widths. More than two may be used or a single spacer strip may be used. The innermost lamination 204 preferably is provided with an inwardly extended pivot socket block 206 for receiving the pivot end 207 of the product hold-down rod 208. Upstanding from the block 206 is a product guide flange 209. This is spaced from the forward edge of the lamination 204 which carries it so that it will always be spaced inwardly of the product stop flange 205 carried by the lamination 204.

It will be apparent that two of the laminated units 200 will be used in association with the respective opposed magazine side walls 52. The ends 207 of the T-shaped rod 208 will extend in opposite directions into the inwardly opening sockets in the two pivot blocks 106. The ends 207 will be of such lengths relative to the sockets that inward and outward adjustment of the lamination 204 can be made if desired. As indicated in FIG. 35 vertical relative adjustment of the various laminations is possible. Also, longitudinal relative adjustment is possible to vary the spacing of guide flange 209 inwardly of stop flange 205 and that of stop flange 205 inwardly of fixed stop flange 55. Also, as indicated, adjustment of the lateral spacing of the two innermost laminations is possible. If desired, spacing shims (not shown) could be used between the various laminations.

Thus, with these various laminations, the plane of ejection may be varied by selective positioning of the additional stop flanges 205 in accordance with the thickness of the product to be vended. The stop flanges 209 and rod 208 may be adjusted to different vertical positions depending on the height of the product to be vended. The lateral spacing of the innermost laminations may be varied in accordance with the width of the product to be vended.

It will be apparent from the above that this invention deals with an article ejecting machine which has article ejecting mechanisms that includes a movable magazine having article stop means adjacent to its ejecting end for engaging and stopping the leading article of a supply of articles disposed in the magazine, the leading article being stopped at a predetermined ejector plane.

The machine also includes means for bodily advancing the magazine to an ejecting position and magazine stop means for engaging the magazine or a part carried thereby to determine the ejecting position thereof and locate the ejector plane in accordance with the thickness of the articles in the magazine so that the ejector elevator finger will move it off the article stop means at the ejecting end of the magazine. According to this invention additional means is provided for varying the location of the ejector plane so that when the magazine is in its ejecting position the ejector plane is positioned at a different location to compensate for the difference in thickness of the articles to be ejected as compared to the thickness of the articles for which the machine was designed. This additional means may include additional stop means contacting with the magazine or a part carried thereby to vary its ejecting position, additional article stop means located in the magazine at its ejecting end and disposed inwardly of the original article stop means on the magazine, or both.

Having thus described the invention, what is claimed is:

1. An article ejecting machine comprising ejector mechanism which includes a movable magazine having article stop means adjacent its ejecting end for engaging and stopping the leading article of a supply of articles disposed in the magazine, said stop means engaging and stopping the leading article at a predetermined ejector plane, means for bodily advancing the magazine to an ejecting position, magazine stop means to determine the ejecting position thereof and locate the ejector plane in accordance with the thickness of the articles in the magazine, ejector means movable in an ejecting stroke to engage the leading article in the magazine and move it off said article stop means, and means for varying the location of said ejector plane so that when the magazine is in ejecting position the ejector plane is positioned to compensate for the difference in thickness of the articles to be ejected.

2. An article ejecting machine according to claim 1 in which said means for varying the location of said ejector plane includes additional magazine stop means cooperating with the magazine to vary its advanced ejecting position.

3. An article ejecting machine according to claim 1 in which said means for varying the location of the ejector plane of the magazine comprises additional article stop means located in the magazine at its ejecting end and disposed inwardly of the first-named article stop means.

4. An article ejecting machine according to claim 2 in which said additional stop means comprises a fixed stop engaging a portion movable with the magazine.

5. An article ejecting machine according to claim 4 in which the first magazine stop means comprises said portion movable with the magazine and movable into engagement with a fixed stop member to determine the advanced ejecting position of the magazine, and the additional magazine stop means comprises a fixed stop plate having a stop portion engaging said portion mov-

able with the magazine before it reaches said fixed stop member.

6. An article ejecting machine according to claim 4 in which the first magazine stop means comprises said portion movable with the magazine and movable into engagement with a fixed stop member to determine the advanced ejecting position of the magazine, and the additional stop means comprises a fixed stop plate engaging another portion of the magazine before the first portion thereof is engaged by said fixed stop member.

7. An article ejector machine according to claim 6 in which the magazine is supported for horizontal reciprocation and the ejector means comprises an elevator carrying an ejector finger for vertical movement, and means for mounting said finger for vertical adjustment on the elevator.

8. An article ejecting machine according to claim 6 in which the magazine includes a guide member carried thereby and operating in a guide slot, said fixed stop plate engaging said guide member.

9. An article ejecting machine according to claim 8 in which said first-named stop means carried at the ejecting end of the magazine comprises laterally spaced flanges between which the ejector means will travel, and additional stop flange surfaces spaced inwardly thereof a distance corresponding to the difference in thickness of the articles.

10. An article ejecting machine according to claim 1 in which said article stop means carried at the ejecting end of the magazine comprises laterally spaced flanges between which the ejector means will travel, said means for varying the location of said ejector plane comprising additional stop flange surfaces spaced inwardly thereof.

11. An article ejecting machine according to claim 10 in which said additional stop flange surfaces are carried by members adjustably mounted on the magazine by lateral adjustment means to vary the spacing therebetween.

12. An article ejecting machine according to claim 10 in which said additional stop flange surfaces are carried by members adjustably mounted on the magazine by adjusting means for movement toward and from the first-named laterally spaced flanges.

13. An article ejecting machine according to claim 10 in which said additional stop flange surfaces are carried by members adjustably mounted on the magazine by adjusting means for lateral movement to vary the spacing therebetween and for movement toward and from the first-named laterally spaced flanges.

14. An article ejecting machine according to claim 13 in which said members providing the additional stop flange surfaces consist of a pair of upright angle members forming an article guide channel therebetween.

15. An article ejecting machine according to claim 14 in which a pair of additional similar upright angle members are provided above the first-named angle members to provide an upward continuation of the guide channel.

16. An article ejecting machine according to claim 15 in which means is provided for adjustably mounting the additional upright angle members for movement longitudinally, laterally and vertically of the magazine.

17. An article ejecting machine according to claim 1 including a pair of upright article guides above said stop means on the magazine, and means for adjusting

said guides for movement longitudinally, laterally and vertically of the magazine.

18. An article ejecting machine according to claim 10 including guide means disposed within the magazine and extending longitudinally thereof to change the effective width of the magazine.

19. An article ejecting machine according to claim 10 including an article hold-down means extending longitudinally of the magazine and spaced above the bottom thereof to engage the upper edges of the articles in the magazine.

20. An article ejecting machine according to claim 10 including guide means disposed within the magazine and extending longitudinally thereof at the opposite

15 sides thereof to change the effective width of the magazine, and an article hold-down means extending longitudinally of the magazine and spaced above the bottom thereof to engage the upper edges of the articles in the magazine.

21. An article ejecting machine according to claim 20 in which said guide means is in the form of a pair of guide rods and said hold-down means is in the form of a rod, means for mounting the guide rods for lateral movement to vary the spacing therebetween, and means for mounting the hold-down rod for vertical movement in the magazine to adjust it for articles of varying heights.

22. An article ejecting machine according to claim 4 30 in which said article stop means carried at the ejecting end of the magazine comprises laterally spaced flanges between which the ejector means will travel, said means for varying the location of said ejector plane including additional stop flange surfaces spaced inwardly of said first flanges.

23. An article ejecting machine according to claim 22 in which said additional stop flange surfaces are carried by members adjustably mounted on the magazine by lateral adjustment means to vary the spacing therebetween.

24. An article ejecting machine according to claim 22 in which said additional stop flange surfaces are carried by members adjustably mounted on the magazine by adjusting means for movement toward and from the 45 first-named laterally spaced flanges.

25. An article ejecting machine according to claim 22 in which said additional stop flange surfaces are carried by members adjustably mounted on the magazine by adjusting means for lateral movement to vary the 50 spacing therebetween and for movement toward and from the first-named laterally spaced flanges.

26. An article ejecting machine according to claim 25 in which said members providing the additional stop flange surfaces consist of a pair of upright angle members forming an article guide channel therebetween.

27. An article ejecting machine according to claim 26 in which a pair of additional similar upright angle members are provided above the first-named angle members to provide an upward continuation of the guide channel.

28. An article ejecting machine according to claim 27 in which means is provided for adjustably mounting the additional upright angle members for movement longitudinally, laterally and vertically of the magazine.

29. An article ejecting machine according to claim 4 including a pair of upright article guides above stop means on the magazine, and means for adjusting said

guides for movement longitudinally, laterally and vertically of the magazine.

30. An article ejecting machine according to claim 22 including an article stop spaced inwardly of said stop flange surfaces a distance corresponding substantially to the thickness of the article being vended, said article stop extending above the vertical extent of said flange surfaces.

31. An article ejecting machine according to claim 30 in which the last-named article stop is in the form of an upstanding flange, and means for mounting said stop flange on the magazine for movement toward and from said stop flanges.

32. An article ejecting machine according to claim 10 including an article stop spaced inwardly of said stop flange surfaces a distance corresponding substantially to the thickness of the article being vended, said article stop extending above the vertical extent of said flange surfaces.

33. An article ejecting machine according to claim 32 in which the last-named article stop is in the form of an upstanding flange, and means for mounting said stop flange on the magazine for movement toward and from said stop flanges.

34. An article ejecting machine according to claim 30 in which the article stop comprises an upright plate supported by the magazine, a pair of angles carried thereby for lateral adjustment to vary the spacing therebetween, and a stop plate carried by the upright

plate between said angles and mounted for vertical adjustment.

35. An article ejecting machine according to claim 10 in which a laminated wall unit is provided within at least one of the side walls of the magazine and extends longitudinally thereof, said wall unit consisting of a plurality of laminations adjustably fastened together and to the side wall of the magazine.

36. An article ejecting machine according to claim 10 35 in which one of said laminated wall units is disposed in association with each of the magazine side walls.

37. An article ejecting machine according to claim 36 in which one or more of said laminations of each unit carries a flange disposed within the respective stop 15 flanges at the ejecting end of the magazine to provide said additional stop flanges.

38. An article ejecting machine according to claim 37 in which the innermost lamination of each side wall laminated unit is provided with an inwardly opening 20 socket to provide a pair of opposed sockets for receiving opposed pivot arms on a T-shaped retaining rod to extend longitudinally of the magazine and engage upper edges of articles thereon.

39. An article ejecting machine according to claim 25 37 in which said means for varying the location of the ejector plane of the magazine comprises additional stop means cooperating with the magazine to vary its advanced ejecting position.
